COMBINED CANDLESTICK AND BRACKET THEREFOR

Donald E. Woerner, Rochester, N.Y., assignor to Rochester Novelty Works, Inc., Rochester, N.Y., a corporation of New York

Filed Dec. 10, 1962, Ser. No. 72,788

Term of patent 14 years

(Cl. 48—2)

FIG. 1 is a perspective view of a combined candlestick and bracket therefor showing my new design, with a fragmentary portion of a pew shown in dotted lines for illustrative purposes only;

FIG. 2 is a side elevation thereof shown in separated position;

FIG. 3 is a top plan view thereof; and

FIG. 4 is a bottom plan view thereof.

I claim:

The ornamental design for a combined candlestick and bracket therefor, substantially as shown and described.
